[57] CLAIM

The ornamental design for a vertical coin slide for attachment to coin operated machines, as shown and described.

DESCRIPTION

FIG. 1 is a top plan view of a vertical coin slide for attachment to coin operated machines showing my new design;

FIG. 2 is a left side elevational view thereof, the right side being a mirror image except that the spring visible in FIG. 2 is hidden;

FIG. 3 is a front elevational view thereof;

FIG. 4 is a rear elevational view thereof; and,
FIG. 5 is a bottom plan view thereof.

Fig. 1.
